T. JACKSON.
MARINE ENGINE GOVERNOR.
APPLICATION FILED JUNE 11, 1919.

1,413,585.

Patented Apr. 25, 1922.

INVENTOR:
Thomas Jackson
By Mr Wallace White
ATT'Y.

UNITED STATES PATENT OFFICE.

THOMAS JACKSON, OF LEWISHAM, LONDON, ENGLAND, ASSIGNOR TO ALLAN RAMSAY,
OF FOLKESTONE, ENGLAND.

MARINE-ENGINE GOVERNOR.

1,413,585.

Specification of Letters Patent. Patented Apr. 25, 1922.

Application filed June 11, 1919. Serial No. 303,466.

(GRANTED UNDER THE PROVISIONS OF THE ACT OF MARCH 3, 1921, 41 STAT. L., 1313.)

To all whom it may concern:

Be it known that THOMAS JACKSON, subject of the King of Great Britain and Ireland, residing at 27 Mount Pleasant Road, 5 Lewisham, London, S. E., England, has invented new and useful Improvements in Marine-Engine Governors, (for which I have filed application in Great Britain November 20, 1917, No. 17,113,) of which the 10 following is a specification.

This invention relates to improvements in marine engine governors, and refers to that class of apparatus in which a gravity controlled element is operated by the movement 15 of the ship to control the action of a power device for operating the throttle valve or other arrangement by which the speed of the engine is regulated. In the past it has been customary to use a tiltable tube containing mercury, or a pivoted device carrying a rolling body, which alters its position when the ship alters its angle with the horizontal, the device being adapted to operate an externally disposed valve or other control 20 device. The present invention is an improved device for effecting the same purpose in a simple and certain manner, which can be manufactured cheaply, be fool-proof in action, and be inaccessible to alteration of 25 action by the impossibility of interference with its active elements, and consists in a device which is rigidly attached to the ship in an adjustable manner having a tiltable control element carrying a mobile body controlled by gravity by which the passage of 30 power medium to the throttle operating gear is controlled by gravity during the angular movement of the ship.

In order that the invention may be the 35 better understood I will now proceed to describe the same in relation to the accompanying drawing, reference being had to the letters and figures marked thereon. Like letters refer to like parts in the various figures, in which:—Fig. 1 is a part sectional view of a device constructed in accordance with this invention.

Fig. 2 is a sectional plan of the casing with the tiltable member removed showing 45 the valve seat and passages for the fluid under pressure.

According to the invention a casing or box *a* is pivotally mounted at *b* upon a fixed sup-

port *c* rigidly attached to the ship or to some device carried by the ship, for example, one of the engine columns. This casing or box *a* is further supported by another support *d* which is adjustable by means of nuts *e* on a screwed stem *f* so that the angle of the box relative to the ship can be adjusted within a given range, and when so adjusted can be rigidly locked in position so that the relative position of the box with respect to the ship is a permanent and rigid one until readjustment is necessary. The nuts *e* may 65 if desired be secured by a suitable device or keeper under lock and key. Within the box *a* is mounted an element *g* which rocks upon a pivot *h* carried in lugs *i* and provided with means such as a trough *j* along which a 70 rolling body or weight *k* can travel, so that when the weight *k* rolls towards one end it tilts the element in one direction, and towards the other end it tilts it in the opposite direction. This rocking element *g* directly carries a valve *l* pivoted at *m* or in turn it may be made to operate a valve not carried by the element *g*; in either case the valve *l* controls the exit *n* from the box. An adjustable stop *o* is arranged in the bottom 75 of the casing to regulate the angular movement of the element *g*. The box *a* is further provided with communicating means such as an orifice *r* connecting through the pipe *p* with some source of fluid pressure for operating or controlling through the pipe *q* the operation of the power device connected to the throttle valve or other regulating arrangement by which the speed of the engine 80 is regulated.

It will be seen by this arrangement that the angularity of the box *a* can be set to the particular trim of the ship so that under normal conditions the throttle valve is not operated, but in the event of the ship altering its angular position so that the rolling weight *k* will run along the rocking element *g* and operate it on its axis, the valve *l* will be opened and the throttle valve gear be operated.

What I claim is:—

In a governor for marine engines in which a power device operates the throttle and is controlled by a device under the control of gravity, the arrangement of a closed casing 105 having an inlet and outlet for fluid pressure

pivoted to a fixed support on the ship, a track pivotally mounted in said casing, a rolling element adapted to run in said track to lift the track when the rolling element is either on one or other side of the pivot, a valve actuated by said track adapted to control the passage of the fluid and adjustable fixing means by which the casing can be angularly adjusted to any position relative to the keel of the ship to give the re-

quired operation of the track actuated valve, substantially as described.

In testimony whereof I have signed my name to this specification in the presence of two subscribing witnesses.

THOMAS JACKSON.
